UNITED STATES PATENT OFFICE.

DANIEL A. LOWNEY, OF SAN FRANCISCO, CALIFORNIA.

DUMP-BODY FOR VEHICLES.

1,109,132.

Specification of Letters Patent.

Patented Sept. 1, 1914.

Application filed September 30, 1913. Serial No. 792,612.

To all whom it may concern:

Be it known that I, DANIEL A. LOWNEY, a citizen of the United States, residing in the city and county of San Francisco and State of California, have invented new and useful Improvements in Dump-Bodies for Vehicles, of which the following is a specification.

This invention relates to a dump-body for trucks, and particularly pertains to a mechanism for operating same.

It is the object of this invention to provide a mechanism for operating a rockable dump-body in which the use of upwardly extending standards or frames of excessive height is obviated, but which, however, is adapted to elevate the free end of the dump-body to a sufficient distance to insure the discharge of the load.

A further object is to provide a mechanism of the above character which is simple in construction and efficient and reliable in operation, and which is so constructed and arranged as to require no shortening of the dump-body to provide space for its application.

Another object of this invention is to provide means for elevating the free end of a pivoted dump-body in which the lifting force will be exerted in the form of a pull substantially in a direction along the line of the arc of travel of the point of application of the power to the dump-body.

Other objects will appear hereinafter.

The invention further consists of the parts and the construction and combination of parts as hereinafter more fully described and claimed, having reference to the accompanying drawings, in which.—

Figure 1 is a partial side elevation of a truck, showing the invention as applied. Fig. 2 is a transverse section and elevation on the line *a—a* of Fig. 1. Fig. 3 is a detail and side elevation of the operating gears.

In the drawings A represents a truck-frame or chassis, and B represents a dump-body pivotally mounted at 2 thereon. The dump-body B is here shown as the end-dump type, which is designed to be elevated at its forward end to discharge its contents from its rear end.

The essence of this invention resides in the mechanism for raising and lowering the forward end of the dump-body, which mechanism consists of a pair of standards 3 mounted on the truck-frame A on each

side of the dump-body B, a pair of hangers 4 rigidly mounted on the sides of the dump-body B forward of the standards 3, a pulley-block 5 on the upper end of each standard 3, a pulley sheave 6 on the lower end of each hanger 4, a cable 7 attached at one end to each hanger 4 and rove over the pulley-block 5, sheave 6, and after once passing over the pulley-block 5 wound upon a drum 8. A drum 8 is provided for each cable 7, and each drum is mounted on a shaft 9 extending transverse of the truck-frame A; the drums 8 being disposed adjacent to the sides of the truck-frame and immediately rearward of the standards 3. The shaft 9 is provided with a beveled gear 10, at a point near its center, which meshes with a beveled pinion 11 on a countershaft 12. The countershaft 12 extends centrally of the truck-frame longitudinally thereof, parallel with the engine drive shaft 13, and has a gear 14 of large diameter on its outer end. A slideable pinion 15 is splined on the drive shaft 13 and is connected to a yoke on the lower arm of a lever 16, the upper arm of which is attached to a rod 17 connecting with an operating lever 18; the pinion 15 being adapted to be moved in and out of engagement with the gear 14 on the operation of the lever 18. The drive shaft 13 is that usually employed on power-driven vehicles and extends from the transmission gear case 19 to a point adjacent the fly-wheel 20 of an engine of any suitable character; a clutch 21, controlled by a foot lever 22, being mounted on the drive shaft 13 and adapted to be thrown in and out of engagement with the fly-wheel 20. The transmission gears in the case 19 are adapted to be shifted by means of a hand-lever 23 in the usual manner to dispose the transmission gears either in a neutral or various chain speed or reverse positions, as is well known.

Mounted on the transverse shaft 9 is a brake-drum 24, around which a band-brake 25 extends, the band-brake 25 being connected to an operating lever 26 disposed at a convenient point on the truck-frame.

In the operation of the invention when it is desired to discharge the load from the dump-body B, the transmission gears in the case 19 are first moved to their neutral position by the operation of the lever 23, thus throwing out the driving connection between the shaft 13 and the drive-wheels of the truck. The hand-lever 18 is then op-

erated to shift the pinion 15 into mesh with the gear 14, whereupon the foot lever 22 is operated to throw the clutch 21 into engagement with the fly-wheel 20 to cause the 5 drive-shaft 13 to be rotated. Rotary motion will then be transmitted through the gear 14, shaft 12, pinion 11 and gear 10 to rotate the shaft 9 and the drums 8, thereby winding the cables 7 on the latter. The 10 cables 7 on winding on the drums 8 operate to hoist or elevate the forward end of the dump-body B into the position indicated in dotted lines in Fig. 1. When the dump-body B has reached its uppermost or dump- 15 ing position the brake-band 25 is caused to frictionally engage the brake-drum 24 by the operation of the hand-lever 26, and when this occurs the foot-lever 22 is released to throw out the clutch 21. When it 20 is desired to restore the dump-body B to normal position, the brake-band 25 is sufficiently loosened to permit the dump-body to gravitate back to its normal position; the speed of travel of the dump-body being 25 regulated and controlled by the hand-lever 26. The pinion 15 is then thrown out of engagement with the gear 14 so as to clear the drive shaft 13 and permit the operation of the drum without affecting the dump- 30 body operating mechanism.

By providing the downwardly extending hangers 4 on the dump-body B, the sheaves 6 will be spaced a considerable distance from the pulley-blocks 5 on the standards 3, thus permitting of a long distance of travel of the dump-body without necessitating the use of high standards or projections on the truck-frame. This arrangement permits of the truck being passed under low bunkers, driveways and the like.

An important feature of the invention resides in the relative arrangement of the hangers 4, standards 3 and drums 8 by which the pull on the hangers 4 will be in a direction nearly conforming to the arc of travel of the point of connection between the cable and the load, thus enabling the expenditure of a minimum amount of power to lift the load. By arranging the hangers 4, standards 3 and drums 8 at the sides of the dump-body B, the latter may be made of any desired length.

While I have shown the invention as ap-

plied to an end-dump-body, it is manifest that it is equally applicable to bodies of 55 the side-dump type.

Having thus described my invention, what I claim and desire to secure by Letters Patent, is:

1. In combination with a truck frame, 60 and a dump body pivoted at its rear end thereto, depending hangers rigidly secured to the sides of the dump body at the front end thereof, a pulley sheave on the lower end of each hanger, upwardly projecting standards rigidly secured to the sides of the truck frame in spaced relation and to the rear of said hangers, a pulley sheave on the upper end of each standard, a shaft journaled in the truck frame and arranged in 70 spaced relation and to the rear of the standards, a drum on each end of the shaft, means to drive the shaft, and a cable for each drum connected thereto and passed upwardly over the respective sheaves of the 75 standards then passed downwardly under the respective sheaves of the hangers then upwardly over the sheaves of the standards and finally downwardly and rigidly secured to the respective lower ends of the 80 hangers.

2. In combination with a truck frame, and a dump body pivoted thereto, uprights at the sides of the frame disposed between the pivotal point of the body and the front 85 end thereof, downwardly extending elements carried by the body and disposed between the uprights and the front end of the body, the lower ends of said elements being offset toward the rear end of the body 90 and the upper ends of the uprights being offset toward the rear end of the body whereby in the up movement of the body the offset ends of the elements will move close to the offset ends of the uprights, and 95 hoisting means connected to the offset ends of the elements and to the offset ends of the uprights.

In testimony whereof I have hereunto set my hand in the presence of two subscribing 100 witnesses.

DANIEL A. LOWNEY.
